Inventor,
John G. Susman,

By Minturn & Minturn
Attorneys.

UNITED STATES PATENT OFFICE.

JOHN G. SUSMAN, OF INDIANAPOLIS, INDIANA.

ART-GLASS JOINT.

Application filed September 7, 1926. Serial No. 133,932.

The object of this invention is to provide a substantial and convenient joint connection between metal window mullions at their intersections, such that one of the mullions 5 may extend continuously across the window frame, for maximum strength, and those running in the opposite direction can be attached at any position along the continuous one or ones, and can be changed at will.

A further object is to provide a connection which can be entirely or partly removed from working position for the sufficient separation of the mullions to allow for the 15 assembly of the glass in the mullion channels or grooves, and then slid on the continuous mullions into final assembly position of the others.

I accomplish the above, and other objects 20 which will hereinafter appear, by the means illustrated in the accompanying drawing, in which—

Fig. 1 is a front elevation of a window utilizing my invention;

25 Fig. 2 is a plan view of a metal blank slotted at the corners preparatory to bending the resulting ears into holding devices;

Fig. 3 shows the same after the ears are bent into holding devices;

30 Fig. 4 shows the opposite side of that illustrated in Fig. 3;

Fig. 5 is a perspective view of a continuous mullion with a pair of my improved clips in position for holding a horizontal 35 mullion, one of which appears in full lines and the other forming its extension, is indicated by dotted lines; and

Fig. 6 is a detail looking at the sides and ends, respectively, of mullions joined by my 40 invention.

Like characters of reference indicate like parts in the several views of the drawing.

All of the mullions are H-shape in cross section, the channels being where the edges 45 of the glass are secured and held by the flanges which define the channels. The glass will be retained without additional means, but may be further secured by putty. The mullions as now commercially procurable 50 are bent to form out of sheet metal strips of zinc, copper, brass or the like.

In the embodiment of my invention here illustrated, the continuous mullions 9 extend from side to side of the window frame 8

and the vertical or cross mullions 7 only 55 extend between the continuous one 9, and are attached to the latter at their intersections by two of my joint pieces 10.

The joint pieces 10 are each formed from a square blank of sheet metal in which slots 60 11, from each corner toward the center of the plate, are made, thereby producing eight ears of acute outer angular form all of which are next bent in the same direction, 65 into parallelism with the body of the piece, thereby producing eight locking ears 12, arranged in four pairs, as shown in Fig. 3. The ears of two diametrically opposite pairs receive one side of an H-shaped mullion 7, between them and the body 10 with 70 a sliding fit, and the ears of the other two diametrically opposite pairs receive one side of the respective ends of two H-shaped ears or horizontal mullions 9.

The joint pieces are used in pairs, one for 75 each side of the H-shaped mullions, and they can be slidingly moved to any convenient working position along the continuous mullions 7, which is particularly desirable in setting the glass 13.

Having thus fully described my invention, what I claim as new and wish to secure by Letters Patent of the United States, is—

1. In a corner fastener for window mullions, a substantially rectangular plate slotted 85 from each corner toward the middle of the plate forming a pair of angular ears at each corner, the ears of each corner pair being bent on the same side of the plate but in opposite directions from each other to 90 receive the flanges of mullions with a sliding fit.

2. The combination, with a sash having mullions which are H shaped in cross section, some of said mullions extending continuously of the window and others in opposite directions between pairs of the continuous mullions, of a fastener at the joints between and connecting the mullions, comprising one or more plates at each joint having 95 two pairs of diametrically opposite ears in pairs, adapted to slide on the continuous mullions and to receive and hold the ends of the other mullions.

In testimony whereof I affix my signature. 105

JOHN G. SUSMAN.
